This application Mar. 22, 1967, Ser. No. 6,415

Term of patent 14 years

(Cl. D26—14)

This application is a continuation of each of applicant's copending applications, Ser. No. D.86,754, filed Aug. 30, 1965, and Ser. No. D.87,427, filed Oct. 11, 1965, abandoned subsequent to filing this application.

FIG. 1 is a front elevation of a loudspeaker showing my new design;

FIG. 2 is a side elevational view of the form shown in FIG. 1, the opposite side being substantially a mirror image thereof; and

FIG. 3 is a front elevation of a modified form of the loudspeaker shown in FIG. 1

FIG. 4 is a side elevational view of the form shown in FIG. 3, the opposite side being substantially a mirror image thereof.

In each embodiment, the rear and top of the loudspeaker are substantially flat and unornamented.

I claim:

The ornamental design for a loudspeaker, as shown and described.
